UNITED STATES PATENT OFFICE.

ALEXANDER M. LEMKE, OF EAST SAGINAW, MICHIGAN.

WOOD-CUTTING MACHINE.

SPECIFICATION forming part of Letters Patent No. 392,126, dated October 30, 1883.

Application filed May 28, 1888. Serial No. 275,309. (No model.)

To all whom it may concern:

Be it known that I, ALEXANDER M. LEMKE, a citizen of the United States, residing at East Saginaw, in the county of Saginaw and State 5 of Michigan, have invented certain new and useful Improvements in Wood-Cutting Machines; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 This invention relates to improvements in refuse-wood-cutting machines, the object and utility of which are to provide a machine for cutting or reducing culls or refuse pieces of wood into fine particles, so as to enable the 20 same to be carried through the ordinary dust-conveyers to the boiler-room to be used for fuel, obviating the time and expense of conveying such material by hand.

Machines of this class as have heretofore 25 been constructed consist of a heavy revolving wheel carrying in its peripheral sides a series of cutting-knives, and is supported in a solid frame-work having at one end a feed-spout with throat-plate, the upper portion of the 30 wheel being inclosed with a suitable case fitted to the frame. The foregoing manner of constructing such machines is found to be objectionable for the reasons as follows: These machines, as a general rule and matter of convenience, are located under the flooring of factories and mills. The revolving wheel employed 35 in these machines is a very heavy structure, weighing from twelve to fifteen hundred pounds, and, being supported in a solid frame-work, can only be removed by the use of hoisting devices, involving much time and expense whenever it is found necessary to examine or repair the journal-boxes or wearing parts; and, further, it is found that frequently chips and 40 pieces of bark are caught and collect between the periphery of the wheel and its inclosing case, where they bind and retard the free action of the wheel, decreasing the power of the machine, producing friction and strain on the 45 journal-bearings, causing them to become heated, and frequently melting the babbittting of the bearing parts.

The foregoing objections are overcome and the objects sought are attained in my present device, as will be seen from the following specification, reference being had to the accompanying drawings, in which—

55 Figure 1 is an isometrical view of the machine as constructed according to my invention, showing the inclosing-case raised and one end of the frame detached to allow the cutting-wheel to be rolled out of its frame. Fig. 2 is a side elevation of Fig. 1, the parts of the inclosing-frame being in section. Fig. 3 is a detail view of the periphery of the wheel, showing the stripping or cleaning pins located in the periphery thereof. Fig. 4 is a detail view 60 of the locking device for securing one end of the case to the frame.

65 In the letters of reference in the drawings, 70 W represents the wheel, which is of the usual form, being rigidly attached to the shaft F, carrying the pulley m, and K represents the cutting-knives secured to the sides of the wheel, the edges of which project through the 75 sides of said wheel in the usual way, as shown in Figs. 1 and 2.

70 D shows the base or supporting frame, S the feed-spout formed integral therewith, and P the throat-plate secured to the bottom plane 80 of the feed-spout, which is also common in this class of machines.

E represents the removable end of the base-frame D, which is secured within the sides of the frame D at one end by means of the screw-threaded bolts 2, which pass through the sides 85 D and enter the screw-threaded holes 3 in the ends of the removable end E, as shown clearly in Fig. 1.

H represents the sides of the inclosing hood 90 or case, which are secured to the circular top or crown plate C by the truss-rods h, passing through the lugs d of the sides H, as shown in Figs. 1 and 2. The rear end of said case or hood is hinged at Z to the lower end of the 95 upper portion of the feed-spout S, as shown clearly in Figs. 1 and 2. The sides H of the case at the forward lower portion are provided with the forked ears e, which are formed integral with said sides, and which, when the 100 case is closed, as shown in Fig. 4, meet with the brackets a of the sides D of the frame carrying the pivoted bolts e, with nuts r, and are received by the ears c, as shown in Fig. 4, and

by tightening said nuts against the upper face of the ears *c* the case may be firmly bound to the frame *D*. Fig. 1 shows a series of screw-threaded bolts or pins, which are passed at intervals through the periphery or flanges *N* of the wheel *W*, as shown clearly in Figs. 2 and 3. Said bolts are to be adjusted so as to clear the inner face of the crown-plate *C* of the case, and when the machine is in operation said bolts act as strippers, and remove all particles—such as chips and pieces of bark—which have in machines as heretofore constructed collected in the space *t* between the case and periphery of the wheel, and thus prevent the wheel from binding and producing friction by the clogging of such matter, as stated. Any suitable form or construction of pin may be used in the periphery of the wheel; but the bolts shown are most preferred, as they may be readily adjusted to compensate for wear and to keep them flush with the inner face of the crown-plate of the case, so as to effectually remove all particles that might tend to lodge. The object of providing the base-frame with the removable end *E* is to enable the cutting-wheel *W* to be readily removed from its bearings to inspect or repair the same by simply removing the end *E*, as shown by dotted lines in Fig. 1, when the wheel may be rolled out of the frame, the case or hood being previously raised, as shown in Fig. 1. The essential features of my invention consist in the employment of suitable stripping pins or bolts, which are located at intervals in the periphery of the wheel, and in the construction, as described, of the supporting frame or case, whereby access to the bearing

or wearing parts for inspection or repairs may be had at will, and to enable the wheel to be readily removed from its frame when desired without the aid of hoisting devices, which has heretofore required considerable time and labor to accomplish.

Having thus fully set forth my invention, what I claim as new, and desire to secure by Letters Patent, is—

1. In an organized wood-cutting machine, the combination of the cutting-wheel, the supporting-frame having the detachable section at one end, and the hood hinged to the feed-spout, its free end adapted to swing upward and from the detachable section of the supporting-frame, as and for the purposes specified.

2. In a wood-cutting machine, the combination of the supporting-frame, the cutting-wheel having two peripheries, the projecting pins in the peripheries thereof, the feed-spout, the hood hinged to said feed-spout, and having means for locking its free end to the frame when closed, as and for the purposes specified.

3. In a device for the purposes specified, the combination of the supporting-frame having the detachable end, with feed-spout attached to the opposite end of said frame, the cover or hood, hinged as set forth, and the cutting-wheel having two peripheries, each periphery carrying a series of cleaning-pins, which pins are adjustably mounted therein, as and for the purposes specified.

In testimony whereof I affix my signature in presence of two witnesses.

ALEXANDER M. LEMKE.

WITNESSES:

HERBERT A. FORREST,
FANNIE MORSE.
